(Cl. D71—1)

To all whom it may concern:

Be it known that Alexander Kartveli and Robert A. Kaiser, citizens of the United States and respectively residents of Huntington Station, Long Island, New York, and Bayside, Long Island, New York, have invented a certain new, original, and ornamental Design for an Airplane, as particularized in the following specification, shown in the accompanying drawings, and claimed in the subjoined claim.

In the drawings:

Fig. 1 is a top plan view of an airplane em-

bodying the present design with the landing-gear protracted:

Fig. 2 is a front elevation thereof with the landing-gear protracted: and

Fig. 3 is a side elevation of the airplane embodying the present design with the landing-gear retracted.

What is claimed is:

The ornamental design for an airplane, substantially as shown.

ALEXANDER KARTVELI.
ROBERT A. KAISER.
